INVENTOR-

Ralph F. Knight.

UNITED STATES PATENT OFFICE.

RALPH F. KNIGHT, OF BEVERLY, MASSACHUSETTS, ASSIGNOR TO UNITED SHOE MACHINERY CORPORATION, OF PATERSON, NEW JERSEY, A CORPORATION OF NEW JERSEY.

GRINDING MACHINE.

1,419,271.

Specification of Letters Patent. Patented June 13, 1922.

Application filed July 19, 1920. Serial No. 397,262.

To all whom it may concern:

Be it known that I, RALPH F. KNIGHT, a citizen of the United States, and resident of Beverly, in the county of Essex and State 5 of Massachusetts, have invented certain Improvements in Grinding Machines, of which the following description, in connection with the accompanying drawings, is a specification, like reference characters on the drawings indicating like parts in the several figures.

This invention relates to grinding machines of the type adapted more especially for grinding the blades of rotary cutters, as 15 for instance, those of heel trimming machines.

The blades of rotary heel trimming and breastcutting cutters have ordinarily been ground on a machine of the type shown in 20 United States patent to Glidden No. 543,647. The rotary cutter heads are provided with a shaft which is inserted in a relatively fixed bearing on the frame of the machine and the blades have been arranged on the cutter 25 head in planes which diverge with relation to the shaft. It has been found that on heel breastcutting cutters the blades so arranged, operate with a scraping action which sometimes leaves a ragged edge on the work 30 where the blades leave the heel. It has therefore been proposed to construct the head with the blades at a reversed angle, that is, to arrange them in planes which converge with relation to the cutter shaft in order 35 that the advance or leading face of the blade may meet the face of the heel at an obtuse angle and thus avoid a scraping cut. Hitherto there has been no machine to grind these 40 reversely arranged blades while in the cutter head.

It is an object of the invention to provide an improved machine which will accurately grind blades to a predetermined shape while in the cutter head. Another object is to 45 provide a machine which will not only grind the blades on reversed cutter heads, but which will also grind the blades of the ordinary cutter heads.

In the preferred embodiment the invention 50 is illustrated as an attachment for a

grinding machine of the type shown in the patent referred to. A movable standard, preferably pivoted, is provided with a bearing for the cutter head shafts, the standard being moved to vary the inclination of the 55 bearing and the shaft, to bring the blades to the proper relation with respect to the grinding wheel. Preferably the contour of the blades will be controlled by a template and former as is usual on machines of the 60 type illustrated in the patent.

Referring to the drawings,

Fig. 1 is a top plan view of that portion of the machine to which my invention relates;

Fig. 2 is a side elevation, partly broken away;

Fig. 3 is a front elevation showing one of the cutter heads in its grinding position;

Fig. 4 is a similar view, showing a different cutter head in its grinding position.

The numeral 10 indicates the grinding wheel mounted on a horizontal shaft 11, and 70 12 indicates a former, the contour of which corresponds to the peripheral contour of the 75 grinding wheel 10. A portion of the usual swinging frame which carries my attachment is indicated at 14 and this frame is provided with sockets into which fit pivot posts 16 and 18 which carry respectively the 80 knife carrier 20 and template carrier 22. These two carriers are connected by the usual link 24 so that the carriers may be simultaneously moved to traverse the template 85 30 across the former 12 and the blade across the grinding wheel. On the template carrier 22 is a slide 26 which may be adjusted by the hand screw 28 and which carries at one end a template 30 for cooperation with the former 12.

Attached to the knife carrier 20 is an apertured bracket 32 having a flange 34 provided with an enlarged flat bearing face upon which slides a similar bearing face formed on a flange 38 of a standard 36, a 95 felt ring being set into one of the faces if desired, to provide for lubrication. The standard 36 is provided with an offset portion having a hollow trunnion 40 engaging the apertured bracket 32 and being held 100

therein by the washer 42 and screw bolt 44. It should be noted that the axis of this trunnion 40 which intersects the grinding wheel and is at right angles to its shaft passes 5 below the axis of the cutter head and is so disposed that the lower blade in the head will be supported in the proper relation to the grinding wheel and template whether the standard is arranged to support the 10 cutter head shown in Fig. 3 or to support that shown in Fig. 4. Mounted in the bracket 32 is a spring-pressed tapered pin 46 manipulated by a handle 48 and this tapered pin is adapted to engage either of the 15 openings 49 or 50 in the standard 36 to lock the latter in the angular position desired. The end of the standard 36 has an inclined bearing 52 to receive the shaft 54 of a cutter head 56 the blades of which are indicated 20 at 58. This cutter head may be of any desired type and can be clamped in the inclined bearing by means of the clamp handle 60. When the head shown in Fig. 3 is to have its blades ground, the spring-pressed pin 25 46 will be inserted in the aperture 50 of the standard 36. This will lock the head in the proper position to bring the lowermost blade 58 parallel with the axis of the grinding wheel and parallel with the template. In 30 Fig. 4 is indicated the shaft 64 of a cutter head 66 to whose blades 68 are arranged at reversed angles with respect to the shaft 64. Whenever these blades are to be ground, the standard 36 will be swung upon its pivot 35 40 and the pin 46 snapped into the other aperture 49 of the standard. This locks the standard in a position to bring the lowermost blade 68 into proper relation to the wheel for grinding. Thus, by an easy manipulation of the standard, the machine can 45 be quickly adapted to grind blades on the different cutter heads.

Having thus described my invention, what I claim as new and desire to secure by Letters Patent of the United States is:

1. In a machine for grinding rotary cutters whose blades have different cutting angles, a grinding wheel and a bearing member pivotally mounted on an axis intersecting the grinding wheel to present the blades of the different rotary cutters in proper relation to the wheel for grinding.

2. In a machine for grinding rotary cutters whose blades have different cutting angles, a shaft, a grinding wheel, a standard having a bearing for the cutter shafts, said bearing being inclined to the axis of the grinding wheel, and a pivotal mounting for the standard extending at right angles to the shaft of the grinding wheel so that the inclination of the bearing may be changed.

3. In a machine for grinding rotary cutters whose blades have reversed cutting angles, a grinding wheel, a standard having

a bearing for the cutter shafts, said bearing being normally inclined to the axis of the grinding wheel, and means constructed and arranged to enable the standard to assume another position with its bearing inclined at a reversed angle with relation to the 65 grinding wheel. 70

4. In a grinding machine having a grinding wheel and connected knife and template carriers, a standard having an inclined bearing and being pivoted to the knife carrier whereby the inclination of the bearing may be changed with respect to the axis of the grinding wheel to provide for the grinding of cutter heads whose cutting blades are 75 differently arranged. 80

5. In a grinding machine having a grinding wheel and connected knife and template carriers, a standard having a bearing inclined to the axis of the grinding wheel to receive the shaft of a rotary cutter, and a trunnion to secure the standard on the knife carrier so that it can be reversely inclined to receive a cutter head having its blades 85 reversed. 90

6. In a grinding machine having a grinding wheel and connected knife and template carriers, a bearing inclined to the axis of the grinding wheel to receive a rotary cutter having cutting blades with a predetermined cutting angle, and means to reverse the inclination of the bearing to receive a rotary cutter having cutting blades with the cutting angle reversed. 95

7. In a grinding machine having a grinding wheel and connected knife and template carriers, a bearing inclined to the axis of the grinding wheel to receive a rotary cutter having cutting blades with a definite cutting angle, and a trunnion securing the bearing to the knife carrier whereby the inclination of the bearing may be reversed to receive a rotary cutter having cutting blades with the cutting angle reversed. 100 105

8. In a grinding machine having a grinding wheel and connected knife and template carriers, a bearing inclined to the axis of the grinding wheel to receive a rotary cutter having cutting blades with a definite cutting angle, a trunnion securing the bearing to the knife carrier whereby the inclination of the bearing may be reversed to receive a rotary cutter having cutting blades with the cutting angle reversed, and means 110 115 to secure the bearing in either position. 115

9. In a grinding machine, a grinding wheel, a knife carrier, an apertured bracket extending therefrom, a standard trunnioned on the bracket and having an inclined bearing for the shaft of a rotary cutter, and means for securing the standard and bearing in different angular positions to hold the different cutters in grinding positions. 120 125

10. In a grinding machine, a grinding

wheel, a bracket supported adjacent to the wheel and having an enlarged flat bearing face, a standard pivoted to the bracket and also having an enlarged flat bearing face, an inclined bearing in the standard to receive the shaft of a rotary cutter head, and means extending through the bracket and engaging the standard to hold the standard and bearing in a plurality of positions on the bracket to provide for the 10 grinding of different cutter heads.

In testimony whereof I have signed my name to this specification.

RALPH F. KNIGHT.
